UNITED STATES PATENT OFFICE.

GEORGE W. JONES, OF CLEVELAND, OHIO.

ROCK-DRILL.

SPECIFICATION forming part of Letters Patent No. 534,692, dated February 26, 1895.

Application filed April 30, 1894. Serial No. 509,451. (No model.)

To all whom it may concern:

Be it known that I, GEORGE W. JONES, a citizen of the United States, residing at Cleveland, in the county of Cuyahoga and State of Ohio, have invented certain new and useful Improvements in Rock-Drills; and I do hereby declare that the following is a full, clear, and exact description of the invention, which will enable others skilled in the art to which it appertains to make and use the same.

My invention relates to rock drills, and the invention consists of the construction and combination of parts substantially as shown and described and particularly pointed out in the claims.

In the accompanying drawings, Figure 1 is a vertical central sectional elevation of the drill supporting and actuating mechanism. Fig. 2 is a vertical elevation of said mechanism with the parts shown in Fig. 1 turned quarter way around. Fig. 3 is a cross section enlarged on line x, x , Fig. 2, looking down. Fig. 4 is a vertical sectional elevation on a line corresponding to z, z , Fig. 6, looking downward. Fig. 5 is an elevation of the parts shown in Fig. 4 with the upper part in section on line y, y , Fig. 6. Fig. 6 is a cross section on a line corresponding to line x, x , Figs. 4 and 5. Fig. 7, Sheet 1, is an enlarged sectional view of parts of the valve mechanism.

The construction here shown comprises a supporting saddle A clamped upon the cross shaft or rod B by clamping screws —2— passing through the jaws —3— of the saddle A. Attached to the said saddle and adjustable as to the angle on the shaft F is the vertical supporting back having a hub —15— upon its rear provided with a beveled flange adapted to engage in a beveled seat upon the face 40 of the saddle A.

The foregoing mechanism is the subject-matter of another application bearing Serial No. 519,808.

The seat on the saddle A is undercut both at the bottom and sides, Figs. 1 and 6, and the flanged hub —15— is inserted from above. A correspondingly dovetailed or beveled cross-piece —16— engages the upper edge of the flange —15— and is held firmly therein by a short locking bolt —18— entering through the slot in the top of hub A; as seen in Fig. 3. By these means, or their equiva-

lent, the parts A and H are made rigid with one another but are also separable.

The mechanism for operating the drill is suspended from the back supporting piece H by means of a long threaded screw rod L, which passes through the head —20— of the support H, and a handled lever —21— serves to turn said screw rod in either direction as the operations of the drill may require. The drill actuating steam cylinder M is supported upon this rod L through the projection —22— at its rear, and this projection, Fig. 6, has lateral flanges —23— which work in guide-ways, grooves or channels in the sides of the back support H, so that as the cylinder and parts are adjusted up and down by means of the threaded rod L they are confined in their proper relation and place by said flanges and channels.

In the steam cylinder M is a reciprocating piston N having heads —24— with inclined or curved surfaces —25— at their base constructed to actuate the valves as hereinafter described. At one side and centrally of the cylinder M is a valve chamber —27— with separate cylindrical, barrel shaped, perforated valves —28— at the ends of said chamber and at right angles to the axis of the piston. These valves have central headed stems —29— projecting inward toward the piston, and a rock bar —30—, pivoted at its center, overlaps these heads at its ends and is itself actuated by the piston N, the inclined surfaces —25— of said piston striking the extremities of the said bar alternately and alternately depressing the valves —28— according as the piston N is moved in one direction or the other. A central diaphragm —26— in valve —28— carries said headed stems —29— and the inlet and exhaust holes are on opposite sides of this diaphragm. Each valve —28— is pressed back by the live steam when pressure by rock bar —30— is relieved. The piston N is connected rigidly with the drill rod O by means of a connecting rod P, which is suitably packed where it passes through the head of said cylinder.

At its upper end the piston N has a central bore extending inward into its neck some distance, and this bore has spiral grooves corresponding in section to the formation of the spiral shaft R. When the drill is carried

down to work it is desirable that the action should be straight and direct without turning, but in order that it shall not strike its successive blows at the same place, but vary 5 the same step by step, I have provided means for rotating the drill slightly on each up or return movement. This consists in a short spiral rod R, supported in the head of the cylinder M by means of a collar or head T rigid 10 therewith and resting upon a plate --32--, forming the immediate head of the cylinder but built in between the part S and the flange of the cylinder. The collar T is set into a recess in the head piece S above plate 32, and 15 around about this collar is a spring clamp --33--, having enlarged extremities --34-- and --35-- projecting laterally into a side recess within head part S. The arm --34-- rests against the side of this recess, while a 20 movable steam actuated cylindrical plug --37-- is adapted to press against the arm --35-- of the said clamping ring. Now, in order that the said ring may be tightened when the piston N is on the up stroke, I provide 25 the said plug --37-- and a steam channel --39-- from the bottom of cylinder M, for steam to enter the chamber behind said plug. This presses the plug --37-- inward and tightens the clamp --33--, thus causing the clamp 30 to lock on the collar T and hold it from turning. Hence, when the piston rises the piston must turn upon the rod R, and their connection being spiral, the piston necessarily must rotate as it rises and thus give a turning 35 movement to the drill. When the piston is on the down stroke the steam is cut off from channel --39-- and plug --37-- and the spiral rod R with its collar T is caused to turn as the piston and the drill make a direct down 40 stroke.

The spirally grooved rod R is adapted to turn in the plate --32-- and when steam enters the chamber above the piston it may also enter the chamber in which the head T and 45 clamp --3-- are located, and in doing so it will drive the plug --37-- back so as to release the said clamp from the head T, if it be not already released; but when the steam exhausts from the chamber above the piston 50 and enters the chamber beneath and acts upon the head of plug --37-- there is no pressure in the clamp chamber and hence nothing to interfere with the action of said plug in locking said clamp on the head T.

Having thus described my invention, what 55 I claim is—

1. The mechanism herein described for rotating the drill, consisting in the steam cylinder and the piston therein, and the drill rigidly connected with said piston, in combination with a steam chamber at the head of said cylinder, a spiral rod extending into the said piston and having a head in the said steam chamber, and a clamp in said chamber about the edge of said head to engage and hold said 65 head and rod from turning, substantially as set forth.

2. The means described for rotating the drill, consisting of the piston and the drill rod connected rigidly therewith, the cylinder in 70 which said piston operates, a chamber outside said cylinder, a head on said rod located in said chamber, and a clamping band in said chamber and a steam actuated plug to tighten said band, substantially as set forth. 75

3. The construction described, consisting of the steam cylinder and the chamber at the head of said cylinder, and a steam duct leading from the bottom of said cylinder to said chamber, in combination with a drill actuating piston in said cylinder having a bore down through its center, a spiral rod working in said bore and provided with a head in the said chamber, a band encircling said head and a steam actuated plug to bear against the end 85 of said band and tighten the same, substantially as set forth. 80

4. The construction described, consisting of the cylinder having a valve chamber at one side thereof, and a barrel shaped valve at each 90 end of said chamber having a central diaphragm, and perforations on each side of said diaphragm entering into said valve, in combination with a piston in said cylinder having heads at its ends, a rock bar between said 95 valves and said piston and pivoted at its center and having its ends projecting into the path of the said piston, whereby when the piston travels back and forth it alternately depresses the ends of said rock bar and actuates 100 said valves, substantially as set forth.

Witness my hand to the foregoing specification.

GEORGE W. JONES.
